UNITED STATES PATENT OFFICE.

VINZENZ SCHWABE, OF PRAGUE, AUSTRIA-HUNGARY.

METALLIC PACKING.

SPECIFICATION forming part of Letters Patent No. 762,202, dated June 7, 1904.

Application filed October 30, 1903. Serial No. 179,144. (No model.)

To all whom it may concern:

Be it known that I, VINZENZ SCHWABE, a subject of the Emperor of Austria-Hungary, residing at Jungmannovo námesti, No. 6, 5 Prague - Karolinenthal, Austria - Hungary, have invented a new and useful Metallic Packing; and I do hereby declare the following to be a full, clear, and exact description of the same.

10 The object of this invention is to provide an improved and simpler form of metallic packing for rods passing through glands, stuffing-boxes, or the like and for similar purposes. It will be fully described with reference to the 15 accompanying drawings.

Figure 1 is a section through stuffing-box packed according to the invention; Fig 2, a detail view of ring *m*; Fig. 3, a detail showing method of withdrawing the flanged ring *w* 20 out of the stuffing-box; Fig. 4, a modified method of closing the stuffing-box; Fig. 5, another method of closing the stuffing-box.

The packing consists of one, two, or more flanged rings *w*, which encircle the rod *s*, each 25 forming with the next an intervening space, by means of which one or more chambers *k* are formed round the rod. In each of these 30 chambers are fitted two rings, one, *e*, formed as a full unsplit ring and the other, *m*, divided into three or more segments which are pressed together upon the rod *s*, which they fit exactly, by a spiral spring *f*. The full unsplit rings *e* are formed with a minimum amount of play *p* 35 between them and the rods *s* and engage, by means of a projecting flange or edge *r*, with the several segments of the adjacent rings *m*, for which purpose the latter rings are suitably stepped. The full unsplit ring *e* is thus supported by the divided ring *m* at right angles 40 to the rod *s*, so that it is prevented from tilting sidewise by its own weight. The flange *r* in order to preserve the elastic capacity of the divided rings *m* is formed so as to allow a minimum amount of play between it and the 45 latter. Both the full unsplit rings *e* and those, *m*, with several segments are fitted accurately in the chambers *k* laterally, but are capable of displacement therein at right angles to the

axis of the rod, so that no unequal friction can take place in consequence of any deflections 50 of the rod sidewise. The full unsplit rings *e* cover the joints *g* of the divided rings *m*, (see Fig. 2,) so that when the divided rings *m* are adjusted, and consequently where the spaces *g* between the individual segments, 55 which later gradually diminish, still possess their original size, the unpacked portion is reduced to a minimum and the raising of the individual ring-segments from the rod is prevented. In order to facilitate the packing out 60 of the flanged rings *w*, the edges are fitted on the inside with a projection *v*, so that they can easily be drawn out of the end of the stuffing-box by means of hooks *z*, as shown in Fig. 3.

The stuffing-box can be closed, as shown at 65 Fig. 1, by means of a simple cover, or, as in Fig. 4, with soft packing inside the cover, or, again, as in Fig. 5, by means of a cover tightly secured and a supplementary stuffing-box for soft packing constructed in the latter. 70

Having now particularly described and ascertained the nature of my said invention and in what manner the same is to be performed, I declare that what I claim is—

1. In metallic rod-packing the combination 75 with the rod, of a stuffing-box and gland, a plurality of flanged rings *w* filling the space between the gland and the bottom of the stuffing-box, a plurality of full, unsplit rings *e*, one in each ring *w* and having a minimum lateral play on the rod, a plurality of segmental rings *m* each fitted into a ring *w* and filling the space between the ring *e* and the next ring *w* or the gland, and a plurality of spiral springs *f*, each surrounding a segmental ring *w*. 85

2. In metallic rod-packing, the combination with the rod, of a ring *w* having a flange provided with an internal shoulder or projection *v*.

In testimony whereof I have signed this 90 specification in the presence of two subscribing witnesses.

VINZENZ SCHWABE.
